UNITED STATES PATENT OFFICE.

CHRIS Z. ALEXANDER, OF REDWOOD CITY, CALIFORNIA.

BARBER'S ACCESSORY.

1,152,870.

Specification of Letters Patent. Patented Sept. 7, 1915.

Application filed December 18, 1914. Serial No. 877,950.

To all whom it may concern:

Be it known that I, CHRIS Z. ALEXANDER, residing at Redwood City, in the county of San Mateo and State of California, have invented a new and Improved Barber's Accessory, of which the following is a specification.

My invention, which in its general nature is an attachment for barbers' chairs, more 10 specifically is designed for providing a bottle, or other reservoir, containing the face washing fluid, plain or perfumed, hidden out of sight and which is so mounted on the chair that the barber can quickly and 15 conveniently receive the desired amount of the fluid in his hand for applying it to the face of the customer.

Again, my invention seeks to provide a simple and inexpensive fluid holding attachment for barbers' chairs which can be 20 readily applied to any of the well known types of barbers' chairs, and which is provided with means, operable by the barber, for ejecting the spray of fluid into the hand 25 that operates the said means, so that a practically predetermined amount of the fluid is ejected from the holder, as desired for use.

Another object of my invention is to provide 30 in a barber's accessory a simple and effective means for holding the fluid container out of sight, on the chair, and in such position that the same may be readily manipulated by the barber for delivering a 35 charge of the fluid in his hand, as desired and in which is included means for incasing the ejecting portion and the actuating member to keep them in a sanitary condition.

With other objects in view that will herein- 40 after appear, my invention consists in the peculiar combination and novel arrangement of the parts hereinafter fully explained, specifically pointed out in the appended claim and illustrated in the accompanying drawings, in which:

Figure 1 is a perspective view of my invention, the same being shown as operatively applied to the upper end of the 50 barber's chair, the cover plate being shown thrown back and the manner of using the device being also illustrated. Fig. 2 is a horizontal section of the same taken on the line 2—2 on Fig. 1, the parts being at the 55 normal position.

In carrying out my invention, the "bottle" or container 1 is preferably in the nature of a flat sheet metal box 1, having lateral apertured ears 10 for conveniently securing the box on the back of the chair ⁶⁰ at the upper or head-rest end thereof, as is clearly shown in Fig. 1. The box has a tubular extension 9 that projects outwardly from the upper end, and in practice is of such length that it extends through the ⁶⁵ leather or back covering 2 of the chair, and the said extension, which forms a filling tube, is normally closed by a screw cap 1. At the lower end, the box has two nozzles ⁷⁰ 3 and 4 arranged in close proximity, to one of which is attached a pumping bulb 5, the other nozzle 3 forming, as it were, an ejecting nozzle.

6 designates an ornamental casing, which includes a fixed portion attached to the back of the chair and which extends transversely, relatively to the box 1, and has a longitudinal opening 60 disposed centrally thereof for the passage therethrough of the bulb ⁷⁵ 5 and the nozzle 3 and the ends of the casing are provided with suitable ears so that it may be fastened to the chair, as at 7.

8 designates a cover plate that is hinged at ⁸⁰ 80 onto the casing 6 and which includes pockets 81—82 into which the outer end of ⁸⁵ the nozzle 3 and the bulb 5 fits when the cover is closed, as shown in Fig. 2, it being understood by providing a cover member and arranging the casing, as shown, the casing forms, as it were, an ornamental closure ⁹⁰ means for keeping the fluid holding and ejecting means normally out of sight and in a perfectly sanitary condition.

By reason of the structural arrangement of the parts that constitute my invention, ⁹⁵ a simple and inexpensive means for holding the face washing fluids is provided for keeping the fluid always at hand and thereby doing away with the necessity of obtaining it from a table or stand and again each ¹⁰⁰ chair carries its individual face washing fluid and from which a practically predetermined quantity of the fluid is drawn off when manipulated by the barber.

In using my device, the cover member is ¹⁰⁵ swung back, as shown in Fig. 1, and the barber squeezes the bulb while holding the palm of the hand shaped for receiving a charge of the fluid, it being understood that under ordinary conditions the compression ¹¹⁰

of the bulb ejects enough of the fluid, as is ordinarily required for the first application to the face. If more is required, a second or third squeezing of the bulb will provide the necessary fluid.

By reason of mounting the reservoir on the back of the chair, in the manner shown and described, it is invisibly held on the back of the chair and by positioning the 10 bulb and the nozzle in the horizontal plane and adjacent each other enables the barber to freely manipulate the bulb for ejecting the fluid in streams onto a towel held in the palm of his hand, the squeezing of the said 15 bulb operating to eject the fluid under pressure in a stream sufficient to saturate the towel held as stated.

Copies of this patent may be obtained for five cents each, by addressing the "Commissioner of Patents, Washington, D. C."

What I claim is:

In combination with a barber's chair having a recess in its back, a reservoir invisibly mounted in the said recess, said reservoir having an ejecting bulb and a discharge nozzle at its lower end, the said chair having an opening in its back through which the said bulb and nozzle project, a casing secured to the said chair over the said opening and including a hinge cover having sockets for receiving the bulb and the nozzle, the nozzle socket serving as a closure for the nozzle and means by which the reservoir may be filled. 30

CHRIS Z. ALEXANDER.
